DESIGN FOR A BOX

Frank McIntosh, New York, N. Y., assignor to
Letheric Incorporated, New York, N. Y., a corporation of New York

Application November 27, 1935, Serial No. 59,789

Term of patent 14 years

To all whom it may concern:

Be it known that I, Frank McIntosh, a citizen of the United States, residing at New York city, in the county of New York and State of New York, have invented a new, original, and ornamental Design for a Box, of which the following is a specification, reference being had to the accompanying drawing, forming part thereof:

In the drawing:

Figure 1 is a top view of a box embodying my design;

Figure 2 is a front view; and

Figure 3 is a side view thereof.

The dominant feature of the design resides in the combination of a flanged base with a rectangular superstructure provided with symmetrically-placed grooves of a contrasting color, which extend from the base up one side to the top, across the top, and down the opposite side to the base.

I claim:

The ornamental design for a box substantially as shown and described.

FRANK MCINTOSH.
